[57] CLAIM

The ornamental design for a straight-running, non-hanging fishing lure, substantially as shown and described.

DESCRIPTION

FIG. 1 is a side elevation view of a straight-running, non-hanging fishing lure showing my new design.

FIG. 2 is a top plan view of the straight-running, non-hanging fishing lure depicted in FIG. 1.

FIG. 3 is a front elevation view of the straight-running, non-hanging fishing lure depicted in FIG. 1.
